Primary Examiner — Keith J Wilson(57) **CLAIM**

The ornamental design for a toothbrush pinch clip, as shown and described.

DESCRIPTION

FIG. 1 is a front top right perspective view of a toothbrush pinch clip showing my new design;

FIG. 2 is a front bottom right perspective view thereof;

FIG. 3 is a front elevational view thereof;

FIG. 4 is a top plan view thereof;

FIG. 5 is a bottom plan view thereof;

FIG. 6 is a front top perspective view thereof;

FIG. 7 is a front bottom perspective view thereof;

FIG. 8 is a front left elevational view thereof;

FIG. 9 is a rear right elevational view thereof;

FIG. 10 is a front right elevational view thereof; and,

FIG. 11 is a rear left elevational view thereof.

The broken line showing a cap, a toothbrush head, and a toothbrush sanitizer vessel in FIG. 6-11 is included for the purpose of illustrating environmental structure and forms no part of the claimed design.
